(57) **CLAIM**

The ornamental design for an ankle brace, as shown and described.

DESCRIPTION

FIG. 1 is a perspective view of an ankle brace;
FIG. 2 is a left side view thereof;

FIG. 3 is a right view thereof;

FIG. 4 is a front view thereof;

FIG. 5 is rear view thereof;

FIG. 6 is a top view thereof; and,

FIG. 7 is a bottom view thereof.

The broken lines illustrate portions of the ankle brace which form no part of the claimed design.
